Albert A. Kickhofel, Detroit, Mich.

Application February 26, 1936, Serial No. 65,902

2 Claims. (Cl. 273—142)

The present invention relates to new and useful improvements in ash receptacles for smokers and has for its primary object to provide, in a manner as hereinafter set forth, an article of this character embodying novel amusement and advertising features.

Other objects of the invention are to provide an ash receptacle or tray of the aforementioned character which will be simple in construction, 10 strong, durable, attractive in appearance, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

20 Figure 1 is a top plan view of the invention.
Figure 2 is a side elevational view.

Figure 3 is a view in vertical section through the invention.

Figure 4 is a view in horizontal section, taken 25 substantially on the line 4—4 of Figure 3.

Figure 5 is a detail view in top plan of the stationary disk.

Figure 6 is a fragmentary view in top plan, showing the central portion of the bottom of the 30 tray.

Figure 7 is a detail view in vertical section through the post on which the disks are mounted.

Figure 8 is a detail view in perspective of the match holder.

35 Referring now to the drawings in detail, it will be seen that the embodiment of the invention which has been illustrated comprises a tray 1 of suitable dimensions and material, the bottom 2 of said tray being provided with supporting 40 feet or pads 3. The tray 1 further includes a marginal flange 4 on which cigar and cigarette holders 5 are mounted. Also mounted on the flange 4 is a holder 6 for book matches, said holder 6 having an opening 7 therein for exposing the usual striking surface with which books 45 of matches are provided.

The bottom 2 of the tray 1 includes a raised central portion 8 having an opening 9 therein. Fixed in the opening 9 is a post 10 having a 50 reduced upper end portion 11 on which a stationary disk 12 is fixed by upsetting or swaging the upper end of said post. The upper end of the post 10 is also radially grooved or notched for a purpose which will be presently set forth.

55 Extending vertically through the post 10 is a

screw 13 the head 14 of which is countersunk in the lower end portion of said post 10, as best seen in Figure 3 of the drawings. Threadedly mounted on the upper end portion of the screw 13 is a knurled knob 15. Secured to the bottom of the knob 15 and encircling the screw 13 is a rotary disk 16 the periphery of which is formed to provide a pointer 17.

It will be observed that the diameter of the rotary disk 16 is less than that of the stationary 10 disk 12. This is to expose advertising indicia 18 on the marginal portion of the stationary disk 12 to which the pointer 17 is adapted to point. Numerals 19 are also provided on the stationary 15 disk 12 inwardly of the advertising matter 18, said numerals being observable through an opening 20 in the rotary disk or spinner 16. Secured to the lower side of the rotary disk 16 is a resilient latch 21 through which the screw 13 passes, said latch having a tooth 22 on its 20 free end portion engageable in the aforementioned grooves or notches in the upper end of the post 10.

The lower end portion of the post 10 which extends through the opening 9 is reduced, as at 25 23. After being inserted through the opening 9, this reduced end portion 23 is upset or swaged, as at 24, for securing the post 10 in position. A washer 25 is provided between the upset or swaged portion 24 and the bottom of the tray 1, 30 as best seen in Figure 3 of the drawings.

In use, the players rapidly rotate or spin the disk 16 and then observe whichever of the numbers 19 is exposed through the opening 20 when said disk 16 comes to a stop. The arrangement 35 of the grooves or notches in the upper end of the post 10 is such that the tooth 22 on the resilient finger 21 will cause the disk 16 to come to a stop with the opening 20 in full registry with one of the numbers 19. When the disk 16 comes to a stop the pointer 17 thereon directs 40 attention to one of the advertising items 18 on the marginal portion of the stationary disk 12.

It is believed that the many advantages of 45 an ash receptacle or tray constructed in accordance with the present invention will be readily understood, and although a preferred embodiment of the device is as illustrated and described, it is to be understood that changes in the details of construction and in the combination and 50 arrangement of parts may be resorted to which will fall within the scope of the invention as claimed.

What is claimed is:—

1. A device of the class described comprising 55

a base, a post rising centrally from said base, a stationary disk mounted on the post, said stationary disk having advertising indicia on its marginal portion and further having numerals 5 thereon arranged concentrically of said post and inwardly of the advertising indicia, a rotary disk of comparatively small diameter mounted on said post above the stationary disk, said rotary disk having an opening therein for exposing to 10 consecutive ones of said numerals in sequence as the disk rotates, and an indicator on said rotary disk for pointing to the advertising indicia on the stationary disk.

2. A device of the class described comprising 15 a base including a bottom, said bottom comprising a raised central portion having an opening therein, a vertical post fixed in said opening, a stationary disk fixed on the upper end portion of the post, said disk having advertising indicia

on its marginal portion and further having numerals thereon arranged concentrically of said post and inwardly of the advertising indicia, a screw extending vertically through the post, an operating knob mounted on the upper end portion of said screw, a rotary disk fixed to the bottom of said knob and encircling the screw, the diameter of the rotary disk being less than that of the stationary disk, said rotary disk having an opening therein for exposing to consecutive 10 ones of said numerals in sequence as the disk rotates, an indicator on the periphery of the rotary disk for pointing to the advertising indicia, and a resilient finger on the rotary disk engaged with the upper end of the post for stopping said rotary disk in predetermined positions relative to the stationary disk. 15
